[57] CLAIM

The ornamental design for food packaging, as shown and described.

DESCRIPTION

FIG. 1 is a plan view of food packaging showing our new design in unassembled form;

FIG. 2 is a front view thereof in assembled form;

FIG. 3 is a rear view thereof in assembled form;

FIG. 4 is a side view thereof in assembled form;

FIG. 5 is a top view thereof in assembled form; and,

FIG. 6 is a bottom view thereof in assembled form.

The broken lines shown on FIG. 1 represent fold lines. The pattern of parallel lines shown in FIGS. 1-6 represent stripes.
